REFRIGERATING UNIT

Harold A. Schulz, Richland Township, Bucks County, Pa., assignor, by mesne assignments, to Hydro Silica Corporation, Gasport, N. Y.

Application November 16, 1939, Serial No. 304,723

15 Claims. (CL 62—126)

This invention concerns a refrigerating unit, and more particularly a unit applied as an enclosure or a conduit to the matter to be cooled, the refrigeration being caused by converting a circulated fluid from a liquid into a gaseous state.

Refrigeration plates are known, which have spaced walls serving to retain the refrigerating fluid, which is circulated therebetween. One object of this invention refers to the improvement of such a plate, as a refrigerating unit. Another object of this invention concerns the assembling and connecting of such plates into compact units serving as enclosures, e. g., conduits or vessels, for the matter to be cooled.

It is important in connection with a plate or the plates here discussed, that any locking or blocking of the flow of the circulated refrigerant be prevented, that a uniform level thereof be preserved up to which it is in a liquid state, and that arrangement be made to allocate such level in a predetermined manner in order to obtain a high degree of efficiency in the function of the plate. In order to obtain these objects, provisions are made in accordance with this invention for the incorporation of risers and headers in the plates or in their assembly, and in coordination of these parts; for the proper appointment of means exciting, starting or activating ebulation, which means are known per se and defined as ebulators; for an enclosure accumulating spilled over liquids and serving to pass them on in the desired state; for a predetermined allocation of an accumulator and its adaptation as an otherwise useful component of the unit; for a preferred allocation of the heat reacting flow control means; and for a lay-out of interconnecting means contributing to the desired results.

Aside from these features directed primarily to the function of the device, the invention also provides improvements in pursuit of numerous objects of efficiency in heat distribution and conservation of low temperature; it is directed further to the provision of a high ratio of useful space to the total space and of ready accessibility; and it conserves simplicity of construction leading to economy in first costs and substantially eliminating all requirement of maintenance and repair.

These and other objects of this invention are attained by improvements, of which one particular embodiment will now be described in detail, such description being however given in illustration and not in limitation of the invention.

In the accompanying drawing such a preferred embodiment of the invention is shown, wherein:

Fig. 1 is a top or plan view.

Fig. 2 is a corresponding front elevation.

Fig. 3 is a larger, cross-sectioned front view.

Fig. 4 is a detail cross-section of a corner, e. g. at the bottom left of Fig. 1, the direction and level of the section being designated in Fig. 3 by the number 4.

Similar numerals refer to similar parts throughout the various views:

In the embodiment of the drawing the refrigerating unit is shown as an enclosure or jacket having a rectangular passage, the refrigerating plates being assembled and extending around such passage. For purposes of construction each of the four sides 11, 12, 13 and 14 of the jacket each of which may represent a refrigerating plate these plates being suitably joined together at their mitered corners, e. g. by a welding operation.

Joints, edges or corners, where parts are brazed or welded together, or are otherwise united are designated in the drawing by the letter *w*.

The lower end of the refrigerating jacket, 11, 12, 13 and 14 may be closed by a pan, which is suitably attached thereto. In the embodiment of the drawing the outer walls 15 of plates 11, 12, 13 and 14 are for instance extended bottom-wise in order to form the pan together with a bottom sheet 17, which interconnects the lower ends of the extensions 16.

The inner walls 18, together with the outer walls 15 form the plates 11, 12, 13 and 14 and close upon the outer walls 15 at their upper and lower edges, by way of seams 19 and 20 for instance.

Except at their very ends the outer and inner walls 15 and 18 extend in substantial parallelism, above the seam 20, the flat refrigerant space 22 between the two walls being preserved by suitable means, for instance depressions 21, which are struck up towards the inside from the inner walls 18 to the width of said space, and which may be suitably engaged upon the outer walls 15, for instance by spot welds.

The space 22 may be enlarged to form risers 24, where the plates 11, 12, 13 and 14 are joined together at their mitered corners. An enlarged cross-section for such risers 24 may for instance be provided for by striking up the marginal portions 23 of the inner walls 18. In the drawing they are bent up in a substantially normal direction, so that the risers 24 are substantially rectangular in cross-section.

Such risers serve to prevent, that during the welding or brazing operation at the mitered corners the space between the inner and outer walls 55 is clogged up. At the same time these risers 24

present means for balancing the level of the refrigerant in the plates, serving as reservoirs, so to speak.

At the top of the plates I also provide an enlarged cross-section, which offers less resistance to the flow of the refrigerating fluid. For such purpose the upper margins 25 of the outer walls 15 are flared out, and the upper margins 26 of the inner walls 18 are rectangularly bent back to meet the ends of the margins 25 at the seams 19. Thus header 27 extends around the full upper circumference of the refrigerating passage, which intercommunicates with the flat spaces 22 of the plates and with the risers 24 at the corners.

The accumulator 28 substantially corresponds in vertical cross-section with the refrigerating plates 11, 12, 13 and 14, except that it lacks the lower extension 10. Nor does the accumulator 28 have risers on opposite ends, but these ends are closed by seams 29, which are for instance similar to seams 20. Except at its upper end, the accumulator does, therefore, never exceed the cross-section of the flat space 22.

In the embodiment of the drawing the accumulator serves as a partition, which is preferably arranged substantially at the center in line with the connecting tubes 36 and 37 and is there connected with the refrigerating casing, so that the path of the refrigerant from the center of one plate 13 to the center of the opposite plate 11 is about the same in both circumferential directions.

Since the accumulator 28 is substantially of the same height as the refrigerating plates of the refrigerating passage, there is clearance between the accumulator and the pan, and similarly clearances may be provided upon opposite sides of the accumulator 28 in the passage, the drawing showing connecting tubes or pipes to be accommodated in said clearances.

For purposes of connections to the outside a window may be provided in the front plate 13, said window representing, for instance a circular opening around which the outer wall 15 and the inner wall 18 of plate 13 are connected along a marginal seam 30. This window opening is closed by a cover plate 31, which is suitably attached, e. g. by welding.

Into plate 31 are welded or brazed an outlet and an intake bushing 32, 33, both of which are adapted, e. g. by an internal thread at the outer ends, for connection to refrigerating machinery.

Bushing 32 is connected by a tube 34 to the header 35 on top of accumulator 28, the tube entering endwise upon said header.

Another connecting tube extends from the intake bushing 33 to the flat space 22 of plate 13 therebelow, said connecting tube 36 being welded into the inner wall 18 of plate 13.

Upon the opposite side of the accumulator 28 a connecting tube 37 connects the lower end of accumulator plate 28 to the header 27 substantially at the center of the adjacent refrigerating plate 11.

The accumulator plate may be supplementarily secured in the refrigerating passage, e. g. by angle plates 38, some of which are shown to extend between the top of the accumulator 28 and adjacent refrigerating plates 11 and 13.

The closed end of a feeler tube 39 is intimately attached, e. g. by brazing, to the accumulator 28, and is shown to extend over about one third of the width of the latter. This feeler sleeve 39 opens to the outside of the refrigerating unit, where it has a flared opening for the purpose of insertion of a heat responsive instrument, like

a thermal couple. The feeler tube 39 may outwardly be suitably supported upon cover 31, where it passes therethrough, e. g. by a rubber bushing 40.

According to this invention means for exciting and accelerating ebulation are accommodated at low points in the refrigerating plates. Various activating materials are suitable for this purpose. If the material, e. g. carbon, is used in the form of thin rods or sticks, they may be extended in a more or less uniform continuity around the refrigerating passage in the plate, so that there is substantially equal activating of ebulation in all parts. In the embodiment of the drawing pieces of rattan reed 41 rest in plates 11, 12, 13 and 14 across the lowest rows of depressions 21, so that they are well exposed to the liquid refrigerant. These ebulators may be deposited in such position before the plates are assembled with each other because they remain serviceable for the life of the plate assembly.

In present day refrigerating apparatus we commonly find some oil originating at the compressor to be admixed with the circulated refrigerant. Such oil has the tendency of causing superheating, because it retards ebulation of the refrigerant. This is overcome by exciting ebulation, e. g. by an ebulator of the instant invention.

But disregarding the direct effect of oil upon ebulation, it must also be considered, that the oil has a tendency to settle where the least amount of refrigeration is required, or where there is the least flow of refrigerant. Where such an oil concentration occurs, normal ebulation is retarded, so that the unit is not allowed to function normally. Nor can this be overcome by temperature control means, such as thermostatic expansion valves. As a matter of fact undue superheating of the evaporated refrigerant causes the control means to actuate the valve admitting additional refrigerant, when this is not required. An excess of refrigerant will flow over into the suction lines where it causes frosting, will further upset the refrigerating system, and may even lead to damage of the compressor.

This is also overcome by providing the ebulators at low points in the refrigerating plates. Because such an arrangement leads to an even degree of ebulation from the bottom up; and the apparatus may be adjusted to provide for liquid refrigerant substantially up to the top of the plates, so that the supernatant oil is readily caused to spill over, whereas the smoothly boiling liquid refrigerant preserves a substantially constant level in the refrigerating plates. This result,—which is of course at the same time also to be attributed to the provision of risers and headers and the box formation of the refrigerating plate,—permits a much more accurate setting of the heat regulated flow control means, so that the desired high level of the liquid refrigerant in the plate does not exist in theory only, but will be actually preserved.

The operation of the embodiment used herein for illustration of the invention will now be reviewed: The liquid refrigerant entering by connecting tube 36 divides in opposite direction, as it enters upon plate 13, one stream reaching plate 11 by way of plate 12 and the intervening risers, whereas the other branch of flow extends around the other side through plate 14 and the respective risers to the plate 11. In this manner substantially all four plates 11, 12, 13 and 14 are filled with the liquid refrigerant, the risers at the corners serving as reservoirs balancing distribu-

tion and facilitating flow from one plate to the other.

The suction circuit extends from bushing 32 by way of connecting tube 34 and headers 35 to the accumulator 28, and from the lower end of the accumulator by way of connecting tube 37 to the header 27, which extends endlessly on top of the refrigerating plates 11, 12, 13 and 14 and fully communicates with all of these plates. The suction applied in the header 27 to the refrigerating plates below is substantially even throughout the header, on account of the generous cross-section thereof. The ebulators 41, which extend around the refrigerating passage in the plates, will cause even ebulation at a low level of all plates under the suction applied by way of the headers 27, and the evolved refrigerant bubbles will carry particles of oil along in their upward path. The oil accumulates on top of the liquid refrigerant and will flow over into the accumulator, from where the gas, rushing at comparatively high speed on account of the limited cross-section of accumulator 28 will readily carry the oil there accumulating together with refrigerant over and out of the refrigerating unit.

The arrangement of the plates in a box-like formation does not only contribute to an even cooling in the surrounded passage and the maintenance of the low temperature in said space, but will also set up an effective protective wall against heat propagated from the space outwardly surrounding the refrigerating unit.

According to the instant invention the heat reactive control means are arranged above the center of the refrigerating unit, a preferred allocation having been found to be in the range substantially between two-thirds and three-quarters of the over-all height of the accumulator above the lower end of the accumulator, in connection with the type of embodiment shown in the drawing. Accordingly the feeler sleeve 38, which serves to receive the heat responsive implement, should be incorporated in the accumulator plate at substantially that level.

Having thus described my invention in detail, yet I do not wish to be limited thereby, except as the state of the art and the appended claims may require, for it is obvious that various modifications and changes may be made in the form of embodiment of my invention, without departing from the spirit and scope thereof.

What I claim is:

1. A refrigerating unit comprising a plurality of refrigerating plates each made of relatively spaced walls, said plates forming the sides of a rectangle endlessly surrounding a vertical passage, said walls being further spaced apart at the corners of the rectangle than at the side portions extending between the corners.

2. A refrigerating unit comprising refrigerating plates having double walls and arranged in rectangular, upright formation, and a horizontal header communicating with the upper ends of said plates, to their greatest width having an overflow below its top level and forming an endless loop.

3. A multi-cornered refrigerating assembly comprising a pair of relatively spaced walls endlessly surrounding a columnar space on all sides, and serving as a jacket accommodating a body of refrigerant, one of said walls being offset relatively to the other at the corners of the assembly, so that in a horizontal plane the jacket is of wider cross-section at the corners than inbetween.

4. A refrigerating unit comprising vertical risers, an endless level header interconnecting the

upper ends of said risers, an overflow on said header and an accumulator plate having spaced walls and an elevated outlet and connected near its lower end with said overflow, so that refrigerant spilled through said overflow accumulates in said plate until withdrawn by way of said outlet.

5. A refrigerating unit comprising vertical risers, an endless header interconnecting the upper ends of said risers, and refrigerating plates having spaced walls and being panelled between said risers and header in full intercommunication with said risers and header, said unit having an overflow outlet on said header and an intake in one of said panelled plates at a point removed from said risers and header.

6. A refrigerating unit having a vertical, tubular passage and comprising an outer wall and an inner wall substantially parallel with said outer wall, said walls forming a jacket for said passage, a header extending around the upper end of said unit and formed in the material of said walls, a hollow partition in said unit serving as an accumulator for the refrigerant and connected at a low point with said header, and a header at the upper end of said partition and having a suction outlet, so that suction applied to said outlet will withdraw refrigerant from said jacket by way of said partition.

7. A refrigerating unit comprising a refrigerating plate assembly forming an upright jacket, an accumulator plate in the jacket formed by said refrigerating plate assembly and connected in series therewith, and a feeler sleeve forming part of said accumulator plate and extending therefrom through said refrigerating plate assembly to the outside.

8. A refrigerating unit comprising a refrigerating plate assembly forming a substantially tubular, vertical jacket, an endless header at the top of said plate assembly and forming a rim around the outside thereof, and an overflow outlet on said header.

9. A refrigerating unit comprising a refrigerating plate assembly forming a substantially rectangular, vertical jacket and having risers of enlarged cross-section at its corners, an endless header at the top of said plate assembly forming a rim around the outside of said plate assembly, and an overflow outlet on said header.

10. A refrigerating unit comprising refrigerating plates having double walls and arranged in rectangular, upright formation, a horizontal header communicating with the upper ends of said plates, having an overflow below its top level and forming an endless loop, and an accumulator having substantially the shape of one of said plates and having an intake at a low point, said intake being connected to said overflow.

11. A refrigerating unit comprising an assembly of relatively spaced, substantially parallel walls surrounding the space to be cooled, risers formed on opposite sides in and a header at the top of said assembly, said risers and header fully intercommunicating with the space between the walls of said assembly and with each other and being wider in cross-section than said assembly, and an intake for a liquid refrigerant opening onto said assembly at a point removed from said risers and header.

12. A refrigerating unit having an outer and an inner wall forming sides of a polygonal receptacle, the inner wall having relatively spaced portions cooperating with the outer wall to form between said walls substantially parallel reentrant columnar spaces of enlarged cross-section

in a horizontal plane projecting at the corners into the space within said receptacle, said columnar spaces serving as reservoirs for a refrigerant.

13. A refrigerating unit comprising a plurality of similar hollow plates adapted to be flooded by a refrigerant and set up to arise from a common base in order to form the walls of a substantially vertical enclosure, one of said plates serving as an accumulator, and the other plates being connected in parallel with each other but in series with said plate serving as an accumulator.

14. A refrigerating unit having a double wall surrounding a space for articles to be cooled, a partition extending across said space and formed of a double wall having edge portions adjacent the first mentioned wall, an inlet for refrigerant connected to the first mentioned wall and an outlet for refrigerant connected to said partition, the first mentioned wall having passages therein connected to said inlet and said partition having passages connected to the first mentioned passages

and to said outlet, the passages and the connections therebetween being arranged to cause a flow of refrigerant from said inlet in parallel around said space and then through said partition to said outlet.

15. A refrigerating unit comprising an assembly extending about a material receiving space and having hollow walls defining refrigerant passages, said assembly having a front position provided with an inlet intermediate its height and width, a hollow partition defining refrigerant passages and extending between front and rear portions of the assembly and located midway the width of the assembly, a conduit arranged to provide for flow of refrigerant from the lower rear corner of said partition to the upper edge of said rear portion at a point adjacent the upper rear corner of the partition, and an outlet pipe leading from the upper front corner of said partition.

HAROLD A. SCHULZ.
